[57] CLAIM

The ornamental design for a spectacle tag, as shown and described.

DESCRIPTION

FIG. 1 is a perspective view of a spectacle tag, showing my new design;

FIG. 2 is an end elevational view, the opposite end being identical thereto;

FIG. 3 is a side elevational view, the opposite side being identical thereto;

FIG. 4 is a top plan view, the bottom view being identical thereto.

The characteristic feature of my design resides in the dumbbell-like shape of the tag.
